DESIGN FOR A FOUNTAIN STENCIL BRUSH

Merritt W. Magann, St. Louis, Mo., assignor to Diagraph-Bradley Stencil Machine Corporation, St. Louis, Mo., a corporation of Missouri

Application December 13, 1944, Serial No. 116,887

Term of patent 14 years

(Cl. D9—2)

To all whom it may concern:

Be it known that I, Merritt W. Magann, a citizen of the United States and a resident of St. Louis, Missouri, have invented a new, original, and ornamental Design for Fountain Stencil Brush, of which the following is a specification, reference being had to the accompanying drawing, forming part thereof, in which

Fig. 1 is a top plan view of a fountain stencil brush showing my new design;

Fig. 2 is a front elevational view thereof; and,
Fig. 3 is a bottom plan view thereof.

I claim:

The ornamental design for a fountain stencil brush, substantially as shown.

MERRITT W. MAGANN.
